Much Shelist

(57) **CLAIM**

The ornamental design for a hoop, as shown and described.

DESCRIPTION

FIG. 1 is a perspective view of a hoop showing our new design.

FIG. 2 is a front elevation view of the hoop of FIG. 1.

FIG. 3 is a back elevation view of the hoop of FIG. 1.

FIG. 4 is a right elevation view of the hoop of FIG. 1.

FIG. 5 is a left elevation view of the hoop of FIG. 1.

FIG. 6 is a top plan view of the hoop of FIG. 1; and,

FIG. 7 is a bottom plan view of the hoop of FIG. 1.

The broken lines showing in the figures are included for the purpose of illustrating portions of the article and forms no part of the claimed design.

1 Claim, 5 Drawing Sheets
